UNITED STATES PATENT OFFICE.

THOMAS BARSHAM CULLEN, OF WOOLSTON, ENGLAND.

CHIMNEY-POT.

No. 909,159.

Specification of Letters Patent.

Patented Jan. 12, 1909.

Application filed October 7, 1907. Serial No. 396,346.

To all whom it may concern:

Be it known that I, THOMAS BARSHAM CULLEN, of No. 1 Johns road, Woolston, Southampton, England, have invented a new and useful Chimney-Pot, and which will act likewise as a ventilator, being applicable for the ventilation of schools, churches, &c.

This invention relates to that class of chimney tops, pots or the like wherein concentric tubes are employed in such a manner that the air exterior of the pot or flue proper is admitted below the outer concentric tube so as to create in its upward passage a suction upon the inner tube and to thereby assist in drawing the air and smoke from the flue and to discharge the same in an upward direction.

According to the present invention, the outer tube is fixed to the bottom flange of the inner tube by stays and to the top of the inner tube by stays or brackets. The stays connecting the bottom of the outer tube with the flange of the inner are of sufficient length to allow of bricks or cement being used for setting the top, and leaves air passages to the bottom of said outer tube, the outer tube being arranged in such relation to the inner tube that the inner extends within the outer to about one-third its length.

In order that the said invention may be readily understood reference is to be had to the following description and accompanying drawing which represents in vertical section a chimney pot constructed in accordance with the present invention.

In said drawings *a*, represents the outer tube connected by stays *b*, to the bottom flange *c*, of the inner tube *d*, which is connected at its top end by stays or brackets *e*, to the outer tube *a*. The bottom of the tube

a, is arranged at such a level that the tube *d*, 40 extends therein to about one-third its length while sufficient space is left between the flange *c*, and the bottom of the outer tube to permit bricks and cement to be used in the setting of the chimney pot without interfering 45 with the passage of air to the interior of said outer tube. The tubes may be made of any suitable material, and may be square, oval or circular in cross section.

The air entering the bottom of the outer 50 tube from the exterior rises to the top thereof and in so doing sucks the air from the chimney by way of the pipe *d*, and discharges the same and with it the smoke in an upward direction.

I claim:

A chimney top embracing an outer tubular member, an inner tubular member, brackets or arms effecting connection between said outer tubular member intermediate of 60 the ends thereof and the upper end of said inner tubular member, said inner tubular member extending into and terminating at its upper end some distance from the lower end of said outer tubular member and spaced 65 off from the latter, said inner tubular member also having a lateral flange at the lower end formed in continuation thereof, said outer tubular member having its lower end arranged some distance above the corresponding 70 end of said inner tubular member, and supporting means for the lower end of said outer tubular member resting upon said lateral flange of said inner tubular member.

THOMAS BARSHAM CULLEN.
